Primary Examiner — Doris Clark(74) *Attorney, Agent, or Firm* — Ulmer & Berne LLP;
 Brian E Turung(57) **CLAIM**

The ornamental design for a concrete connector, as shown and described.

DESCRIPTION

FIG. 1 is a left side elevation view of a concrete connector of the present application;

FIG. 2 is a right side elevation view of the concrete connector of FIG. 1;

FIG. 3 is a top plan view of the concrete connector of FIG. 1;

FIG. 4 is a bottom plan view of the concrete connector of FIG. 1;

FIG. 5 is a front end elevation view of the concrete connector of FIG. 1; and,

FIG. 6 is a back end side elevation view of the concrete connector of FIG. 1.

1 Claim, 2 Drawing Sheets(56)
